UNITED STATES PATENT OFFICE.

LEWIS B. GAWTRY, OF NEW YORK, N. Y.

DRY GAS-METER.

1,070,679.

Specification of Letters Patent. Patented Aug. 19, 1913.

Application filed December 13, 1912. Serial No. 736,464.

To all whom it may concern:

Be it known that I, LEWIS B. GAWTRY, a citizen of the United States, residing at New York, in the county of New York and State of New York, have invented certain new and useful Improvements in Dry Gas-Meters, of which the following is a specification.

The invention relates to dry gas meters of the type wherein the gas is admitted to a chamber of known capacity and in bellows form, which chamber in expanding and contracting actuates suitable indicating mechanism.

15 The invention consists in constructing the bellows with a flexible wall impervious to gas on its inner side, but on its outer side, spongy and absorptive of oil, so that through the action of capillary affinity, said wall may be much more rapidly saturated with oil and the oil more efficiently retained therein, than has hitherto been found practicable.

20 In the accompanying drawings Figure 1 is a front view of a dry gas meter of known construction, wherein the bellows is shown in place. Fig. 2 is a front view, and Fig. 3 an edge view of the bellows. Fig. 4 shows a portion of the bellows rim, and illustrates a bridge of spongy material disposed across the joint in the flexible wall of the bellows. Fig. 5 is an enlarged view in section of a portion of the flexible wall, supporting rings, diaphragms and meter casing.

25 Similar letters of reference indicate like parts.

As ordinarily constructed, the bellows or working chamber of a dry gas meter comprises two metal diaphragms A, B, secured in rings C, D. The flexible peripheral wall 30 E of the bellows has its ends secured together at F, and is attached at its edges to the diaphragms A, B. Before the band is put in place it is usually stretched over an annular former, so as to give it an outward bulge or fold G. One of the diaphragms, 35 as A, is free to move, so that when the gas under pressure enters the bellows and expands the same, the band tends to flatten, and when the gas escapes it resumes its 40 original shape.

The material of the flexible wall is usually leather of such closeness of texture as will render it impervious to gas under pressure. For this reason and also because the wall 45 must be soft and pliable so as to offer only a negligible resistance to the movement of the

free diaphragm by the entering gas, the heavier or thicker leathers, such as ox-hide or calf-skin are not suitable, and therefore sheep-skin is generally found best adapted to the purpose. In order to maintain the 50 impervious quality by filling the pores which exist, and also to insure the desired flexibility even of sheep-skin, it is necessary to keep the leather saturated with oil, usually a 55 good lubricating oil; otherwise the leather dries and hardens, thus impairing the sensitivity of the chamber in yielding to the gas pressure, and hence its accuracy as a measuring device, and, in time, owing to the 60 constant opening and closing of the fold G, the leather itself cracks, thus causing leaks which result in incorrect registration, thus 65 destroying the utility of the meter.

For many reasons it is not practicable to 70 oil the leather before securing it in place as a part of the bellows. Because of its necessary thinness, oiling renders it soft and slippery, so that handling of whole skins thus treated is difficult and troublesome, nor can 75 bands cut from the skins be oiled prior to being attached to the diaphragm rings. In order to make gas tight joints, each edge of the band is secured to the rings by a wrapping of strong cord H put on tightly, and 80 then covered with an impervious coating of hard varnish or shellac. Oil soaked into the pores cannot be wholly driven out by pressure, although it will in time evaporate. Hence if the band be previously saturated, 85 the joint becomes pervious to gas. So also the protective coating of varnish or shellac cannot be made properly to adhere to the oiled surface. Hence the band is applied to the rings dry, and the strong constriction 90 of the cords compresses it permanently, so closing the pores while the firmly adhering varnish covers and protects the entire joint.

As the chief objects sought have been imperviousness and flexibility, and as the grain 95 side of the leather offers a smoother surface, and hence apparently one less likely to gather dust and impurities, it has hitherto been customary to attach the band in place with the grain side outermost, and to apply 100 the oil to this side. To saturate the band with oil in this way, has always been a long process, for obviously oil will not go into a surface already impervious to gas except with extreme slowness. It takes ordinarily 105 from six weeks to two months to effect proper saturation, besides repeated appli-

cations of the oil, and the latter in turn requires personal attention and expenditure of time. In large instalments where thousands of meters are in use, this delay and time loss is economically serious, in point of cost. To leave meters idle for the time necessary at present to saturate the leather is expensive, the care and attention incident to the oiling is expensive, and inasmuch as throughout the United States over 300,000 sheep-skins per year are used for these leather bands, the aggregate losses due to the foregoing causes attain large figures, irrespective of those incident to the difficulties of re-oiling, or to the constant oversight which is required to prevent injury to the thin kid-like bands, should too long a time happen to elapse after the degree of saturation has fallen below proper limits. Where a meter is put in a house cellar, as it often is, near a furnace, the drying out of the thin leather if not properly saturated and so maintained is apt to be rapid, and thus local conditions may also complicate the difficulties of keeping the band in proper state. I have discovered that all of this trouble can be efficiently overcome by making the flexible wall of the bellows impervious to gas under pressure on its inner side, and spongy and hence absorptive of oil on its outer side. Then when the oil is applied to the spongy outer surface—even if the total thickness of the wall be very small—it will be drawn by capillary affinity into the outer spongy stratum, and rapidly spread throughout the same, so that I have obtained even a better saturation of the band in thirty-six hours than I have hitherto got in six weeks. The re-oiling can be made automatic by simply permitting the lower part of the band to dip in a quantity of oil I, placed in the bottom of the meter casing L, the new oil then being drawn into the spongy outer layer of the skin to replace whatever amount may have evaporated.

I may construct the flexible wall in accordance with the foregoing description in various ways—as, for example, by employing a material spongy throughout and applying an inner impervious coating; but the simplest and hence the preferable expedient is to attach the present sheep-skin band to the diaphragm rings, so that the flesh side shall be outermost. The spongy layer on the flesh side, even of so thin a skin as sheep-skin, is quite absorptive enough when a good free-flowing lubricating oil is used, to become thoroughly saturated within the brief period before mentioned. The saturation

can be somewhat hastened by encircling the flexible wall with a strip of material more absorptive than the spongy layer itself—such as lamp wick—which will take up the oil rapidly and then deliver it to the band around the entire periphery of the latter. Two wicks may be used, as shown at J, K, Fig. 5, and held at the edges of the band in any suitable way, as by the already present wrapping cords. The wick in this case also bridges the joint at the ends of the band, so that the oil will cross over the joint by the wick from one end of the band to the other, and not be stopped by the joint which, if secured by cement, may act as a dam. If the encircling wick or wicks are not desired, the joint can be bridged by a short section M of wick or spongy leather laid in contact with the band and held by the cord on one side, as shown in Fig. 4.

I claim:

1. A dry gas meter, having a bellows comprising a flexible wall of leather, with its flesh side outermost.
2. A dry gas meter, having a bellows comprising a flexible wall of leather, with its flesh side outermost, and means for supplying oil externally to said wall.
3. A dry gas meter, having a bellows comprising diaphragms, an annular band of leather secured at its edges to said diaphragms, with its flesh side outermost, means for uniting the ends of said band, and a bridge piece of spongy flexible material secured to said band and extending across the joint at said ends.
4. A dry gas meter, having a bellows comprising diaphragms, an annular band of leather secured at its edges to said diaphragms, with its flesh side outermost, means for uniting the ends of said band, and a strip of spongy flexible material in contact with and encircling said band.
5. A dry gas meter, having a bellows comprising diaphragms, an annular band of leather secured at its edges to said diaphragms, with its flesh side outermost, means for uniting the ends of said band, and strips of spongy flexible material in contact with and encircling said band and respectively in proximity to the opposite edges thereof.

In testimony whereof I have affixed my signature in presence of two witnesses.

LEWIS B. GAWTRY.
